THOMAS S. HOMANS, OF HEMPSTEAD, NEW YORK, ASSIGNOR TO INTERTYPE CORPORATION, OF BROOKLYN, NEW YORK, A CORPORATION OF NEW YORK.

ASSEMBLER-ENTRANCE FOR TYPOGRAPHICAL MACHINES.

1,331,343.

Specification of Letters Patent. Patented Feb. 17, 1920.

Application filed November 15, 1919. Serial No. 338,273.

To all whom it may concern:

Be it known that I, THOMAS S. HOMANS, a citizen of the United States, residing at Hempstead, in the county of Nassau and State of New York, have invented new and useful Improvements in Assembler - Entrances for Typographical Machines, of which the following is a specification.

The present invention relates to improvements in typographical machines and more especially to those of the linotype class using circulating matrices which are stored in a magazine and from which the matrices drop when released onto a delivery belt which conducts them to the assembling mechanism. The object of the invention is to provide a novel and improved guide to receive the matrices as they leave the magazine and to direct them properly to the delivery belt, although the matrices may be so close to one another in the adjacent channels at the lower or discharge end of the magazine that the matrices may engage or contact with one another, the invention being particularly applicable to a machine using relatively thick matrices bearing large type characters such as those employed for advertising or display printing, as liability of conflict between such matrices and the guide, especially at the point where the matrices leave the magazine and enter the guide, is avoided.

Heretofore typographical machines of the linotype class have been constructed to handle relatively thin matrices. Recent developments of such machines, however, have been made with a view to adapting such machines to the handling of relatively thick matrices bearing large type characters suitable for advertising or display purposes. In constructing a machine capable of handling these relatively thick matrices, it is desirable that the magazine to contain the thick matrices should have the same outside dimensions as the standard magazines in order that the magazines may be interchanged in the machine to meet the requirements for different kinds of type composition. In adopting such a standard for the dimensions of a magazine to handle relatively thick matrices, the space at the lower or delivery end of the magazine has been found to be so limited that in order to accommodate the necessary number of matrices in the maga-

zine, substantially all of such space must be utilized and in some instances, the matrices in one channel of the magazine will touch or contact with the matrices in an adjacent channel of the magazine, as the matrices in these adjacent channels occupy their lower-most position at the bottom of the magazine in readiness to be delivered therefrom. Inasmuch as it is necessary to maintain the matrices in a vertical position, while dropping from the magazine to the delivery belt, the partitions in the guide which is arranged between the magazine and the delivery belt, must reach to within a very short distance of the lower or delivery end of the magazine, in order that the partition will engage the matrix as the lug thereof leaves the channel in the magazine and thus guide the matrix into its proper path, the partitions in the guide serving to prevent twisting of the matrices while passing to the delivery belt. Owing to the very close proximity of the matrices in adjacent channels and at the lower or delivery end of the magazine, it has been found impracticable to extend the partitions of the guide into close proximity to the magazine, in the usual manner and to taper the partitions so finely as to separate or divide the adjacent contacting or closely arranged matrices.

The present invention provides means whereby relatively thick matrices of the kind referred to may be accommodated in a magazine having the usual or standard dimensions of the magazines constructed to contain the ordinary relatively thin matrices, and these relatively thick matrices are so received and guided, that as they are released from the magazine, they are caused with certainty to drop correctly and in the proper paths, without liability of twisting while on their way to the assembling mechanism, and without conflict between the matrices and the partitions of the guide.

To these and other ends the invention consists in certain improvements and combinations and arrangements of parts, all as will be hereinafter more fully described, the features of novelty being pointed out particularly in the claims at the end of the specification.

In the accompanying drawing—
Figure 1 is a perspective view of the

lower portion of a magazine, a portion of the delivery belt and a portion of the assembler entrance which is interposed between the magazine and the delivery belt, 5 the matrix guiding partitions of the assembler entrance being constructed in accordance with the present invention,

Fig. 2 is a profile of the upper portion of one of the matrix guiding partitions of the 10 assembler entrance, and

Fig. 3 is a fragmentary view representing a portion of the lower end of the magazine, taken in section, and the upper portion of the assembler entrance, illustrating the 15 manner in which the relatively thick matrices are grouped in the magazine, and the operative position of the matrix guiding partitions.

Similar parts are designated by the same 20 reference characters in the several views.

The present invention is applicable generally to typographical machines of the class employing circulating matrices which are stored in the channels of a magazine 25 and which drop, when released, from the magazine onto mechanism which conveys the matrices to the matrix assembling mechanism. The invention is particularly applicable, however, to typographical machines of the linotype class, the preferred embodiment of the invention being shown in the accompanying drawing, and hereinafter described in detail. It is to be understood, however, that the invention is not restricted 30 to the precise construction shown, as equivalent constructions are contemplated and will be included within the scope of the claims.

In the present instance, 1 designates a portion of the matrix magazine which, in 40 machines of the linotype class, occupies a downwardly and forwardly inclined position on the machine, the magazine comprising essentially upper and lower plates having complementary grooves 2 which receive 45 the lugs m' on the corners of the matrices M , the grooves or channels in the magazine thus guiding the matrices from the upper end of the magazine where they are received from the distributor to the lower end of the 50 magazine, from which matrices are delivered when required, under the control of a keyboard, the construction and operation of which are well understood in this art. The standard magazines used in machines of 55 this class to contain the ordinary relatively thin matrices, are reduced in width toward the lower or discharge end, in consequence of which the matrix guiding grooves or channels in the upper and lower plates of 60 the magazine converge and become more closely spaced at the bottom than at the top of the magazine. In order that magazines containing relatively thick matrices, such as those bearing large type characters used for 65 advertising or display purposes, may be

used interchangeably in machines adapted to receive the usual magazines containing the ordinary relatively thin matrices, the magazine for the relatively thick matrices preferably has the same outline and exterior 70 dimensions as the usual magazines containing the ordinary matrices so that these magazines may be used interchangeably on the same machine or the same type of machine. Owing, however, to the increased thicknesses of the matrices used and the necessity 75 of utilizing all of the available space at the lower or discharge end of the magazine, the matrices in adjacent channels of the magazine will be in very close proximity and, in 80 some cases may touch or contact with one another at the lower or discharge end of the magazine. This will be understood from Fig. 3 of the drawing, wherein m , f , w and y designate relatively four groups of 85 matrices contained in adjacent channels of the magazine, the matrices f and w being in contact with one another, or so closely grouped that no appreciable space exists between the bodies of these matrices. 90

The matrices released from the lower end of the magazine drop by gravity onto an inclined delivery belt 3 which may be of the kind used in machines of the linotype class for conveying the matrices to the assembling 95 mechanism, this belt passing around an upper pulley 4 by which the belt may be driven and also around a similar lower belt, not shown. The assembler entrance 5 which is interposed between the lower end of the 100 magazine and the delivery belt serves to receive the matrices from the magazine and to control them during their descent, in order that the matrices will be properly deposited on the delivery belt. The assembler entrance comprises a rear curved plate 6 and a similarly curved front plate 7, these front and rear plates of the assembler entrance being spaced sufficiently to permit the matrices to descend in edgewise position between them. Twisting of the matrices while dropping through the assembler entrance, is prevented by a series of guiding partitions 8 which are fitted between the front and rear plates 6 and 7 of the assembler entrance. 105 These partitions or guides 8 are spaced sufficiently close to one another to prevent the matrices descending between them from tumbling over in a flatwise direction, as the matrices drop from the magazine to the delivery belt. Heretofore it has been customary to extend these partitions or guides, for their full width, up to the magazine, because when the matrix left the magazine channels it would be free to turn and twist, and hence 110 it would strike against the end of the guide unless the guide extended sufficiently close to the magazine to prevent such action. While these guides or partitions may be extended for their full width into close prox- 115 120 125 130

imity to the magazine when the usual or relatively thin matrices are used, such a construction cannot be used when the magazine contains matrices which are so thick that 5 those in one channel of the magazine will touch or nearly touch the matrices in an adjacent channel, because the matrices would then wedge against the end of the body portion of the guide if the matrices came into 10 contact with the guide before the front lug of the matrix was clear of its channel in the magazine. The present invention provides a construction whereby the front lug of the matrix will be clear of its guiding channel 15 in the magazine before the matrix reaches the guide or partition, and liability of matrices on either side of the guide or partition striking or stopping against the end of the guide, is prevented. These results are accomplished by providing a matrix guide or 20 partition 8 having the upper end 9 of its body terminating at a distance from the lower or discharge end of the magazine and having a narrow or shallow extension or 25 finger 10 which lies close to the rear plate 6 of the channel entrance, this finger or extension being sufficiently narrow or shallow as to permit the body of a matrix to pass over it. The purpose of this will be understood 30 clearly from Fig. 3. Taking the groups or matrices *f* and *w* for example, it will be observed that these groups of matrices are in lateral contact or substantially so. The matrices *f* are intended to drop at the left- 35 hand side of the middle guide or partition 8 while the matrices *w* are intended to drop at the righthand side of this middle guide or partition 8. The shallow finger or extension 10 on this middle partition will engage 40 the downwardly projecting lug on the forward lower corner of the matrix *f* as the latter is released from the magazine, and this matrix will be thereby directed to the lefthand side of the guide or partition 8. 45 In order to insure the guiding of the matrices *f* to the lefthand side of the middle guide or partition 8, the narrow or shallow finger or extension 10 thereof is bent slightly to the right, as shown. The matrices *w*, 50 however, are intended to descend at the righthand side of the middle partition 8 in Fig. 3, and while a portion of the body of the matrix *w* is in line with the finger or extension 10 of this middle guide, the body 55 of the matrix *w* nevertheless will pass over the finger or extension 10 without catching thereon, and hence each matrix *w* will descend in the passage-way between the middle guide 8 and the next guide to the right 60 thereof in Fig. 3. By this construction of the upper end of the guides 8, the matrices may be grouped very closely in the lower end of the magazine and some of the matrices, such for example, as the matrices *f*, in 65 Fig. 3, may be in line with the guides 8 so that ordinarily such matrices would strike and stop against the upper end of the guide. However, by providing the upper ends of the guides with the narrow laterally deflecting fingers or extensions 10, to engage the 70 forward corner lugs of the matrices, the latter are deflected to the proper side of the guide, and the bodies of adjacent matrices may pass over these fingers or extensions without liability of catching thereon. 75

I claim as my invention:—

1. In a typographical machine of the class adapted to use a magazine having channels for guiding matrices by their projecting lugs, a guide for directing matrices when released from the magazine, the guide having a portion arranged to engage the projecting lug of a matrix released from the channel of the magazine and to direct such matrix to one side of the guide, said portion being 80 so constructed as to lie beneath the body of a matrix released and discharging from an adjoining channel of the magazine.
2. In a typographical machine, the combination of a magazine grooved to receive and 85 guide matrices by lugs which project from the bodies of such matrices, and guides for directing matrices to the point of assemblage as they are released from the magazine, said guides being each provided with a finger 90 arranged to lie wholly under the plane of the body of a matrix and disposed to engage the projecting lug of an adjacent matrix to direct the latter to the point of assemblage. 95
3. In a typographical machine of the 100 class adapted to use a magazine channeled to receive and guide matrices by lugs which project from the bodies of such matrices, a guide for directing matrices released from the magazine to the assembler mechanism, 105 said guide having a body portion and a finger which extends from the body portion of the guide in an upwardly and laterally inclined direction, said finger lying in the path of the projecting lugs of the matrices 110 delivered from one channel of the magazine whereby such matrices are directed to one side of said guide, the finger being sufficiently narrow to permit the bodies of 115 matrices delivered from an adjacent channel of the magazine to pass it and to descend at the opposite side of the guide.
4. In a typographical machine of the class adapted to use a magazine channeled to receive and guide relatively thick closely 120 grouped matrices by lugs which project from the bodies of such matrices, guides for directing the matrices released from the magazine to the assembler mechanism, each guide comprising a plate forming a body portion and a narrow extension projecting in an upwardly and laterally inclined direction from the upper end of said body portion, said extension being arranged to 125 engage the projecting lugs of matrices re- 130

leased from one channel of the magazine and thus direct such matrices to one side of the guide, and the extension lying beneath the bodies of matrices released from an adjacent channel of the magazine to permit such matrices to pass without obstruction to the opposite side of the guide.

In testimony whereof I have hereunto set my hand in presence of two subscribing witnesses.
